UNITED STATES PATENT OFFICE

HUGO JUNKERS, OF DESSAU, GERMANY

AVIATION MOTOR

Application filed June 29, 1920, Serial No. 392,838, and in Germany November 11, 1916.

My invention refers to motors and more especially to the motors used in connection with flying machines designed for use at high altitudes. It is a particular object of my invention to provide a motor capable of developing a constant turning moment at all altitudes within a certain range, from sea-level up to the highest altitude attainable by the machine.

10 When flying machines are designed to work mostly in great altitudes it is necessary to drive them by the aid of motors which retain their full power in these altitudes contrary to normal motors whose power decreases with increasing altitude.

In the motor according to the present invention the piston or pistons have a somewhat larger diameter than the pistons of a normal motor of equal output designed to work only 20 in air of about one atmosphere absolute pressure; that means that for instance the cylinder section of the new motor is to that of the normal one as the inversion of the density of the atmosphere at the altitude in which the 25 flying machine is to work is to the density of the air on the surface of the earth. All other dimensions e. g. those of the driving gear remain almost identical. Thus the new motor is bound to develop under otherwise equal 30 conditions the same power at a certain altitude as the normal motor on the surface of the earth. In order to ensure an unvarying output in the intermediate regions between the earth and the normal working height and 35 to prevent the new motor from being damaged by overstraining within the regions of higher density of air a regulating appliance must be inserted in the pipe admitting the air for combustion to the motor which preferably automatically reduces the pressure, i. e. 40 the quantity of the air admitted to the cylinders, to such an extent that the pressure upon the piston cannot exceed a reasonable limit.

The insertion of an automatic regulator 45 offers the important advantage that the throttling or air admission does not depend upon the attention and care of the machinists so that by rapidly and frequently changing the height the motor can neither be imperilled 50 by overstraining through admitting air of

too high a density nor be weakened inadvertently through heavy throttling in air of lesser density.

The process can be applied to two-cycle as well as to four-cycle motors. From two- 55 cycle motors the combustion gases must be sucked off while the machine works in air of high density so as to allow the throttled air to be sucked into the cylinder at low pressure. For four-cycle motors e. g. a throttling valve 60 can be arranged which is to be inserted in the air admission pipe, influences all cylinders connected with this pipe and is adjusted automatically according to the varying density of air; or the regulating machinery can be 65 arranged so that it influences the time of the opening of the suction valves (or slides) of the cylinders or of the charging pump in such a manner that these will be kept open 70 for a lesser percentage of the piston stroke in denser than in thinner air.

In the drawings affixed to this specification and forming part thereof devices embodying my invention are illustrated diagrammatically by way of example.

In the drawings:

Fig. 1 is a longitudinal section of a device for regulating the tension of the inlet valve spring in proportion to the altitude,

Fig. 2 discloses diagrammatically by way 80 of example a regulating device for use with the motor according to the present invention, and

Fig. 3 discloses a two-stroke cycle engine embodying the principles of my invention.

Referring to Fig. 1, 1 is the air suction pipe leading to the cylinders. A throttling valve 2 is inserted in this pipe which acts under pressure of a spring 3, the resistance of this spring is to be overcome by the admitted air. 90 As the air enters the admission pipe 4 under the pressure of the surrounding air, this pressure after passing valve 2 is reduced according to the tension of spring 3. So the degree of throttling can be adjusted to the varying 95 density of air in different heights by altering the pressure resting on the valve corresponding to the density of air; in the present case this can be done by shifting the resting plate 5 of spring 3 by an appliance influenced by 100

the outer air pressure so that the pressure resting on the valve decreases with the decreasing outer air pressure. The adjusting appliance consists of a diaphragm body 6 closed completely and filled with a gas of some tension which remains practically the same. The pressure of this gas is balanced by the pressure of the outer air plus a variable force e. g. the tension of spring 7 or the imminent elasticity of the diaphragm. As the density of air lessens, spring 7 is compressed by the surplus pressure of the diaphragm until its tension plus the outer air pressure keeps balance to the pressure inside the diaphragm body. The ensuing movement of the diaphragm end plate is imparted to the resting plate 5 by means of the rod 8; as spring 3 rests upon this plate the tension of the former lessens. It is equally advisable to evacuate the diaphragm body 6 so as to eliminate the influence of temperature as far as possible. Instead of imparting the movement of the diaphragm end plate immediately to the appliance for altering the valve pressure, some arrangement can be made by means of which the movement of the diaphragm body brings into action some auxiliary gears (so-called servo-motors) which alter the pressure resting upon the throttling valve or influence the admission valves or slides of the motor.

A certain deficiency of this arrangement consists in the fact that the admission of fuel is worked by means of a carburetter. From ordinary carburetters, if working in air of lesser density, different mixtures are obtained from those working in air of higher density. Though some carburetters have been designed which are alleged to be free from these deficiencies such carburetters are rather complicated as a rule and need a very careful handling. Besides it is highly probable that it is the low temperature in higher altitudes that prevents a perfect gasification.

These deficiencies can be avoided by admitting the fuel not through a carburetter but in measured quantities for each piston stroke; this can be done for instance by means of a fuel pump working synchronously with the motor or by positively moved valves to which the fuel is admitted under an even pressure, or by other means. Here the quantity of fuel admitted for every working stroke and every cylinder should not exceed the amount which can be perfectly consumed by the amount of air admitted at great height, preferably the height mostly used for flying (normal altitude).

A motor thus arranged if compared to a motor fitted with a carburetter has the advantage that the fuel consumed remains exactly the same at all altitudes so that a fairly equal turning moment of the motor is assured from the surface of the earth to normal altitude. As then the fuel admission does not

depend upon the amount of air admitted and does not exceed the amount needed by the motor to develop full power at great height, an overstraining of the motor in air of higher density is made impossible without using any appliances for regulating the admission of the combustion air.

It is principally indifferent whether the fuel is admitted into the suction pipe, into the cylinder or (with two-cycle motors) into the charging pump. The fuel can be admitted at any pressure and so be sprayed very finely so as to assure a perfect gasification under the most adverse conditions. If required the dispersion can be further improved in a well known manner by injecting the fuel by means of highly compressed air.

When the flying machine oversteps the height at which (the air admission not being throttled) the quantity of the fuel injected per stroke is completely used up a surplus of fuel would be injected. In order to save fuel in such cases and to avoid formation of soot, an appliance can be added which, when this height is overstepped, throttles the admission of fuel for every stroke in the same degree as the density of air decreases.

In flying at lesser height, i. e. in air of higher density such a motor will have a surplus admission of air which increases with decreasing height above the surface of the earth. If this surplus air is considered detrimental to a perfect combustion or if the ignition capacity of the mixture should suffer by it, the addition of an appliance is advisable which within the span between the surface of the earth and normal flying height throttles the admission of combustion air to the motor automatically so far that a good mixture is ensured. For this purpose the appliances mentioned farther above can be used. In the present case this regulation of the air admission is not intended to avoid an overstraining of the gear in lower regions, but it serves to obtain a better mixture.

Both appliances, i. e. that for throttling the fuel admission when overstepping the normal altitude and that for throttling the air admission when flying under this height, can be fitted on the same motor. In order to simplify matters one appliance only can be arranged to cause the movement of the regulator which below normal altitude merely influences the admission of combustion air and above it merely the admission of fuel.

Referring now to Fig. 2 the fuel is admitted by pump 20 which sucks liquid fuel from a tank 21 and transports it through pipe 22 to the ejector nozzle 23 which e. g. may be inserted in the suction pipe 1. The pump is driven by a shaft 30 coupled with the motor. When overstepping the normal altitude the fuel admission is reduced by shifting towards the left the eye joint 31 of a lever 32 set in motion by shaft 30; hereby the useful part of the

stroke of piston 25 is reduced which controls the admission opening 26 by its edge 24.

Within the range of higher density of air the quantity of combustion air admitted into the cylinders with each stroke is regulated in the same way as described in above by altering the pressure exerted on a valve inserted in the air suction pipe leading to the motor. 1 is this air suction pipe leading to the motor, 10 2 the throttling valve, 3 the spring pressing upon it whose pressure must be counteracted by the air streaming in from outside 4 the admission branch which the air enters at barometrical pressure. The tension spring 3 is 15 altered by shifting the spring resting plate 5.

The diaphragm body 6 which is airtight and exposed to the outer air pressure serves as a combined organ starting the movements of both regulators; this diaphragm is compressed when near the surface of the earth and expands with increasing height. Rigidly tied to diaphragm 6 is the body 18 which so takes part in its movements; it has two grooves 15 and 17 following the centre lines 20 25 14 and 16 and guiding the arms 11 and 13 of two angular levers; the grooves are partly leading in the direction of the movement of body 18, partly in oblique lines. One of these angular levers (12, 13) in altering the position of eye joint 31 with its arm 12 influences the output of pump 20. Arm 10 of the other angular lever (10, 11) holding the spring rest 5 influences the tension of spring 3 by its movement.

35 The machinery is shown in the position maintained in working at normal heights; air and fuel admission remain uninfluenced. When the machine ascends further the diaphragm expands further and shifts body 18 to the right. The end of lever 13 sliding in groove 17 is hereby shifted downwards by the obliquity of the groove into the position marked by dashes; the eye joint 31 of lever 32 moves to the left, the useful part of the 40 45 50 pump stroke and by this the fuel admission are reduced. The end of lever 11 sliding in groove 15 moves along the horizontal part of this groove, lever 10, 11 remains in position and spring 5 remains loose so that the air is admitted to suction pipe 1 without any hindrance.

When on the other hand the working height of the motor is reduced the diaphragm 6 is compressed by the increasing air pressure and body 18 shifts toward the left. Now lever 11 is turned upwards (into the position marked by dots and dashes) by sliding in the oblique part of groove 15; by doing so spring rest 5 is shifted from its 55 60 65 normal position and spring 3 is compressed so that the air sucked in by the motor has to overcome the resistance of the spring. Arm 13 of the angular lever 12, 13 regulating the fuel admission slides meanwhile in the horizontal part of groove 17, keeps its nor-

mal position and so leaves the fuel admission uninfluenced.

By means of the appliance previously described it is possible to regulate either fuel or air admission by a single appliance carrying out or starting the regulating motion. Instead of imparting the regulating movement of this appliance directly to the regulators some auxiliary gear may be put in for setting the regulators in motion.

Fig. 3 shows the invention as applied to a two-stroke cycle engine. The cylinder 30, only the essential parts of which are represented in the drawing, has an admission port 31 and an outlet 32 arranged as usual. The regulating device described with reference to Fig. 1 is connected to the admission port 31, the same letters of reference being used as in Fig. 1. A suction pump 34 is connected to the outlet 32 by means of a pipe 33, said pump having its piston 35 connected to the crank shaft 37 of the engine by the connecting rod 36 in such manner that at the moment where the engine piston 38 uncovers the outlet 32, the pump piston 35 will exert a sucking action, thus causing a reduced pressure in the engine cylinder 30 to be produced, while the air of combustion flows in through the regulating device 1—8, its quantity being regulated in the manner above described, viz being throttled as long as the engine is working in air of higher density than corresponds to an output which the transmission gear can take up without getting too heavily strained. The regulation of the fuel supply can be effected either by a carburetor or by a pump, as above described.

I claim:

1. An internal combustion engine comprising in combination, a cylinder, a piston reciprocable therein, means connected with said piston for converting its rectilinear motion into rotary motion, means for supplying said cylinder with fuel and air, the diameters of said cylinder and piston being such as to allow of developing the full power, which said converting means can take up continuously, with part of the quantity of air which said cylinder is capable of holding at atmospheric sea-level pressure, means for operating the motor in a two-stroke cycle, means for automatically regulating the composition and quantity of mixture supplied to said cylinder in dependency upon the varying density of the outer air and means for sucking off the gases of combustion from said cylinder, so as to create within said cylinder a vacuum corresponding to the throttling action of said supplying means.

2. An internal combustion engine comprising in combination, a cylinder, a piston reciprocable therein, means connected with said piston for converting its rectilinear motion into rotary motion, means for supplying said cylinder with air, the diameters of

- said cylinder and piston being such as to allow of developing the full power, which said converting means can take up continuously, with part of the quantity of air
- 5 which said cylinder is capable of holding at atmospheric sea-level pressure, means for automatically supplying within certain limits of density of the outer air a constant quantity of non-vaporized fuel for each
- 10 working stroke and means dependent on the density of the outer air for automatically reducing the quantity of fuel in correspondence to a greater decrease of density of the outer air.
- 15 3. An internal combustion engine comprising in combination, a cylinder, a piston reciprocable therein, means connected with said piston for converting its rectilinear motion into rotary motion, means for supplying said cylinder with air, the diameters of said cylinder and piston being such as to allow of developing the full power, which said converting means can take up continuously, with part of the quantity of air
- 20
- 25 which said cylinder is capable of holding at atmospheric sea-level pressure, means for supplying within certain limits of density of the outer air a constant quantity of non-vaporized fuel for each working stroke, and
- 30 means dependent upon the density of the outer air for automatically regulating the quantity of air supplied to said cylinder, so as to automatically reduce the quantity of air supplied to the correct proportion
- 35 for full combustion.
4. An internal combustion engine comprising in combination, a cylinder, a piston reciprocable therein, means connected with said piston for converting its rectilinear motion into rotary motion, means for supplying said cylinder with air, the diameters of said cylinder and piston being such as to allow of developing the full power, which said converting means can take up continuously, with
- 40
- 45 part of the quantity of air which said cylinder is capable of holding at atmospheric sea-level pressure, means dependent upon the density of the outer air for automatically regulating up to a predetermined minimum
- 50 density the quantity of air supplied, means for supplying within certain limits of density a constant quantity of non-vaporized fuel for each working stroke and for reducing said quantity in proportion to the quantity of air admitted in every instance, when said minimum density is overstepped, both said fuel and said air reducing means being under the influence of said regulating means.

60 In testimony whereof I affix my signature.
HUGO JUNKERS.
